US00D980355S

(12) **United States Design Patent** (10) **Patent No.:** **US D980,355 S**
(45) **Date of Patent:** **** Mar. 7, 2023**

(54) **EXERCISE APPARATUS**

(71) Applicant: **Jaquish Biomedical Corporation**,
Nevada City, CA (US)

(72) Inventors: **John Paul Jaquish**, Nevada City, CA
(US); **Paul Edward Jaquish**, Nevada
City, CA (US); **Henry David Alkire**,
Nevada City, CA (US)

(73) Assignee: **Jaquish Biomedical Corporation**,
Nevada City, CA (US)

(**) Term: **15 Years**

(21) Appl. No.: **29/813,392**

(22) Filed: **Oct. 28, 2021**

Related U.S. Application Data

(62) Division of application No. 29/712,411, filed on Nov.
7, 2019, now Pat. No. Des. 937,369.

(51) **LOC (14) Cl.** **21-02**

(52) **U.S. Cl.**

USPC **D21/686**

(58) **Field of Classification Search**

USPC D21/694, 686, 679, 669, 695, 690, 676,
D21/671, 662

(57) **CLAIM**

The ornamental design for an exercise apparatus, as shown and described.

DESCRIPTION

FIG. 1 is a perspective view of an embodiment of our new design of an exercise apparatus;

FIG. 2 is a front view of the design of FIG. 1;

FIG. 3 is a back view of the design of FIG. 1;

FIG. 4 is a top view of the design of FIG. 1;

FIG. 5 is a bottom view of the design of FIG. 1;

FIG. 6 is a first side view of the design of FIG. 1; and,

FIG. 7 is a second side view of the design of FIG. 1.

The broken lines illustrating the band in the above described Figures are for illustrative purposes only and form no part of the claimed design.

1 Claim, 7 Drawing Sheets
